UNITED STATES PATENT OFFICE

JAMES G. McNAMARA, OF BROOKLYN, NEW YORK, ASSIGNEE TO MERGENTHALER LINOTYPE COMPANY, A CORPORATION OF NEW YORK

LINE CASTING MACHINE

Application filed March 20, 1930. Serial No. 437,294.

This invention relates to line casting machines of the general organization represented in U. S. Letters Patent to O. Mergenthaler, No. 436,532, wherein circulating matrices are selected and assembled in line together with expanding spaces, and the line thereafter presented to the front of a slotted mold, expanded or justified between a pair of confining jaws, and finally, after the casting operation, elevated from the jaws and distributed.

In practice, it is necessary to change frequently the length of the slugs or linotypes produced, according to the width or measure of the page or column to be printed. Consequently, the mold slot in which the slugs are cast is made variable in length, and one of the confining jaws is also made adjustable to correspond, so that lines of one length or another may be used at will. Ordinarily, the movable jaw banks directly against one end of a toothed rod by which it is sustained during justification of the line, the said rod being rigidly supported in the vise frame but capable of longitudinal adjustment to locate the movable jaw in its different positions.

While such arrangement of the parts answers all requirements of the art, including that of permitting the movable jaw to be shifted over against the opposing jaw without disturbing the original adjustment of the toothed rod (as may frequently be desired when casting blank slugs), these toothed rods may protrude from one to five inches beyond the left end of the vise cap in the regular 30 em machines and from one to seven inches in the special 42 em machines, according to the length of the lines being cast, and are thus not only in themselves exposed to damage but seriously obstruct the passage in and around machines.

The present invention is intended to obviate these and other difficulties and at the same time enable the operator while seated at the keyboard to adjust the movable jaw to any

required measure with the same speed and facility as heretofore. To this end, the toothed rod is fixedly mounted and confined entirely within the limits of the vise frame, and the movable jaw is supported, not by the rod directly, but by an intermediate sustaining member which is adjustable along the rod and is movable at will into and out of locking engagement therewith. The operation of the said sustaining member is controlled by a second rod concealed mostly within the vise cap and extending somewhat beyond the same at the right so as to be in plain view and within convenient reach of the operator while seated at the keyboard.

In the preferred embodiment of the invention illustrated, the sustaining member is mounted in a slide or carriage to which the inner end of the operating rod is connected, and the latter is provided with an eccentric pin adapted by a half-turn of the rod in opposite directions to actuate said member. At its opposite end, the operating rod is flattened or recessed at the front and back so as to accommodate a pair of inverted scales, graduated in ems and fractions thereof, which may be read in conjunction with a fixed indicating finger or pointer as the rod is moved endwise to adjust the slide and the sustaining member.

In the accompanying drawings, the invention has been shown merely in preferred form and by way of example, but obviously many changes and variations may be made therein and in its mode of application which will still be comprised within its spirit. It should, therefore, be understood that the invention is not limited to any specific form or embodiment except in so far as such limitations are specified in the claims.

Referring to the drawings:—

Fig. 1 is a top plan view showing the improved means for adjusting the left hand line confining jaw, the supporting frame being indicated by broken lines;

Fig. 2 is a front view of the parts shown

in Fig. 1, but partly in section to show the manner of mounting the toothed rod;

Fig. 3 is an enlarged vertical cross-section taken on the line 3—3 of Fig. 2;

Fig. 4 is a horizontal section taken on the line 4—4 of Fig. 3;

Fig. 5 is a detail perspective view of the exposed end of the operating rod to show the scale attached to the back of said rod; and

Fig. 6 is a view similar to Fig. 5, showing the scale attached to the front of the operating rod.

A composed line of matrices and spacers when presented at the casting level is confined endwise between a pair of vise jaws A, B, which are carried respectively by angular blocks A¹, B¹, mounted in a stationary portion C of the so-called "vise frame." The block A¹ is formed with bearing portions A², A³, slidably mounted in suitable guideways C¹ (Fig. 3), so that the left-hand jaw A may be moved horizontally toward and from the fixed opposing right-hand jaw B to vary the distance therebetween according to the length of the matrix lines employed.

In order that justification of the lines may take place properly, it is necessary that the jaw A be located at the proper distance from the opposing jaw to receive a line of a given measure and be supported in such position so as to sustain the line when the spacers are expanded. This is usually accomplished by the use of a round toothed rod D against which the jaw abuts and which may be adjusted endwise and locked in the different positions required.

In the present instance, however, this rod D is relatively fixed or substantially so (being capable only of the slight endwise movement necessary to relieve a justified line from the pressure of the jaws immediately after the casting operation), and is formed as usual (see particularly Figs. 1 and 2), throughout a given portion of its length with circumferential teeth d, the rod being mounted in horizontal bearings C², C³, spaced apart and projecting rearwardly from a bracket C⁴ secured to the vise frame C.

The bearing C² is split and provided with a screw bushing C⁵, which is anchored therein by means of a clamping screw c. At its outer end, the bushing C⁵ is formed with a knurled head portion C⁶ and, for reasons about to appear, terminates at its opposite end slightly beyond the inner side of the bearing C². At a point between the said bearings and immediately adjacent the bearing C³, the rod D is provided with a collar D¹ keyed thereto by a pin d¹ and abutting against a vertical reciprocating wedge E, the latter being supported facewise by the inner end of the bushing C⁵ through an intermediate anti-wear shoe E¹, which serves also to guide the wedge in its vertical movements.

The collar D¹ is held resiliently engaged

with the wedge E by a compression spring C⁷ seated in a recess c¹ of the bearing C³ and which tends to keep the rod D in its normal position. In rising, the wedge E is adapted to move the rod D slightly to the right against the tension of the spring C⁷ so as to position the jaw A exactly to measure preparatory to the expansion of the line between the jaws, and in descending, the wedge allows the spring to retract the rod D a similar distance in order that the line may be lifted readily from between the jaws for distribution, immediately after the slug has been cast.

Occasionally, bastard slug measures are desired, which require an auxiliary adjustment of the left-hand jaw A in fractions other than a half-em, and at such times the clamping screw c in the bearing c¹ is loosened and the bushing C⁵ by means of the knurled knob C⁶ is turned to adjust the rod in one direction or the other to the slight extent desired. Accuracy in such adjustments is obtained by the use of a dial plate C⁸ with which the bushing C⁵ is usually provided and which is read in connection with an appropriate mark on the bearing C².

The means employed for adjusting the jaw A to standard slug measures, which latter may vary in ems and half ems from one to five or from one to seven inches in the different commercial machines, and the means for locking the jaw in its adjusted positions, will now be described. While the rod D is fixed, it is adapted nevertheless, as before stated, to take the thrust of the jaw A indirectly through an intermediate sustaining member F, which, according to the present invention, is mounted independently of the jaw A in such manner that it may be adjusted along the rod D and moved into and out of locking engagement therewith.

As best shown in Figs. 3 and 4, the sustaining member F is mounted in a carriage or slide G arranged at the left of the supporting block A¹ of the jaw A and formed with a bearing portion G¹ which, like the bearing portions of the block A¹, is mounted in the guideways C¹ of the vise frame C. The carriage G is formed in its bottom face with a fore and aft recess G² wherein the member F is confined and which is provided with a retaining plate G³ for holding the said member in place. At its rear end, the sustaining member F is formed with a head portion or block F¹ presenting a horizontal half round toothed concavity F² and a square banking surface f, the latter being aligned with the jaw A, and the teeth of the block F¹ being adapted by a slight endwise movement of the member F in opposite fore and aft directions to make and break a locking engagement with the teeth d of the rod D. While the member F is herein shown as arranged to make direct contact with the jaw A, this is not absolutely necessary, as some other part

of the carriage G could be used for that purpose.

When the member F is moved forwardly, its engagement with the toothed rod D is broken to permit the carriage G to be shifted horizontally in the guideways C¹ for setting the jaw A in the desired position, but when the member F is moved rearwardly, it is caused to re-engage the rod D so as to sustain the jaw A in the shifted position of the carriage G. In this connection, it may be observed that the jaw A is formed with a bottom recess a to clear the rod D and is mounted independently of the carriage G, so that in the production of slugs of any given measure, it may be moved at will from a normal position against the sustaining member F over against the opposing jaw B to permit casting of blank slugs and then moved back to its original position, without necessitating a readjustment of the carriage and sustaining member, as might otherwise be required.

The shifting of the carriage G and the operation of the member F is effected by means of a horizontal actuating rod H which is concealed mostly within the vise frame C, but which extends somewhat beyond the same at the right so as to be in plain view and within convenient reach of the operator while seated at the keyboard. As best shown in Fig. 4, the rod H at its inner end is journalled in the carriage G and near its outer end is similarly supported in a bearing plate C⁹ secured to the vise frame C. Although freely rotatable in the carriage G, the rod H is anchored thereto against any other relative movement and hence is capable, when moved endwise to and fro in the bearing plate C⁹, of shifting the carriage in the guideways C¹. This connection, as herein illustrated, is established by means of a retaining plate G⁴ fastened to one side of the carriage G and shaped to fit over the rod H into an annular groove h formed therein. The movement of the carriage G and rod H toward the left is limited by a stop pin g projecting from the opposite side of the carriage and arranged to contact with the fixed bracket C⁸, while the movement of said parts toward the right is limited by the jaw B through the jaw A and the block F¹ of the sustaining member F.

The inner end of the rod H terminates immediately adjacent the sustaining member F and is provided with an eccentric pin h¹ located in a vertical notch f⁴ formed in said member, the arrangement being such that when said rod is given a half turn in a counter-clockwise direction the member F will be moved rearwardly into locking engagement with the rod D, and when the rod is given a similar turn in the other direction the member F will be retracted to break its engagement with the rod. The rotary movement of the rod H in both directions is arrested by a stop pin g¹ (shown by dotted lines

in Fig. 3), and the sustaining member F is maintained yieldingly in its locked or unlocked position by a detent G⁵, the latter (see Fig. 4) being also mounted in the carriage G and arranged to engage one or the other of a pair of recesses f²—f³, formed in the side face of the sustaining member.

To facilitate the operations of the rod H, it is provided at its outer extremity with a small crank handle h², which, incidentally, permits considerable leverage to be manually applied when turning the rod to move the member F into and out of engagement with the toothed rod D. Consequently, and since the toothed rod D (as may also be observed) is comparatively small in cross-section and projects from six to eight inches beyond its point of support, it would be likely to yield under the contact with the member F if the teeth of the latter, as a result of an inaccurate adjustment of the carriage G, fail to register properly with the teeth d of said rod. In such event, the sustaining member would probably slip back a tooth during justification and require a readjustment of the parts. For this reason, the carriage G is formed with an arm G⁶ (Figs. 1, 3 and 4) through which the rod D is passed and which is intended to give the latter the rigidity required.

In order to determine the position of the carriage G and the sustaining member F with reference to the rod D when the rod H is moved bodily endwise, two scales H¹, H², of the ordinary type and graduated in ems and half ems are secured in shallow longitudinal recesses h³ formed in the front and rear sides of the rod H at the right end thereof. It will be noted (see Figs. 5 and 6) that the two scales are arranged in inverted relation to each other and are adapted to be read separately in connection with an indicating finger or pointer c² secured to the bearing plate C⁹, the scale H¹ being visible in the normal position of the parts to determine a previous setting of the sustaining member F, and the scale H² being brought into view by a half rotation of the rod H to determine the position of said member during its adjustment.

It will now be seen, according to the foregoing arrangement, that when an adjustment of the left-hand jaw A is required, it is merely necessary to give the operating rod H a half turn, move it bodily endwise, and then turn it back to its original position. By the first operation, the eccentric pin h¹ is swung downwardly and forwardly so as to withdraw the sustaining member F from engagement with the toothed rod D, and as the pin h¹ banks against the stop pin g¹, the detent G⁵ enters the recess f³ and holds the sustaining member in its disengaged position (see dotted lines, Fig. 3). The carriage G may then, by the second operation, be shifted in the guideways

C¹ without danger of interference between the teeth of the sustaining member F and the rod D, and with the aid of the scale H² and the pointer c², adjusted to any predetermined position with the sustaining member F in operative relation to the rod D. By the third and final operation, the movement of the eccentric pin h¹ is reversed and the sustaining member F is pushed thereby rearwardly to reengage the teeth d of the rod D. The scale H¹ at the same time is brought again into view, and the detent G⁵ by its engagement with the recess f² serves to restrain the member F against accidental displacement from its locked position. While there are thus three distinct operations performed in setting the adjustable jaw in a new position, these operations are all carried out by the use of a single operating member, and may be performed with one hand without requiring the operator to leave his seat at the keyboard.

Having thus described my invention, what I claim is:—

1. In a line casting machine, the combination of an adjustable line confining jaw, a relatively fixed toothed rod, and an intermediate member mounted independently of the jaw for sustaining the latter in different adjusted positions, said sustaining member being adjustable lengthwise of and relative to the toothed rod and movable into and out of locking engagement therewith.

2. In a line casting machine, the combination of an adjustable line confining jaw, a relatively fixed toothed rod, an intermediate member mounted independently of the jaw and adjustable lengthwise of and relative to the toothed rod for sustaining the jaw in different adjusted positions and movable into and out of locking engagement with the toothed rod, and means for operating said sustaining member.

3. In a line casting machine, the combination of an adjustable line confining jaw, a relatively fixed toothed rod, an intermediate member mounted independently of the jaw and adjustable lengthwise of and relative to the toothed rod for sustaining the jaw in different adjusted positions and movable into and out of locking engagement with the toothed rod, and unitary means for adjusting, locking and unlocking said sustaining member.

4. In a line casting machine, the combination of an adjustable line confining jaw, a relatively fixed toothed rod, an intermediate adjustable member mounted independently of the jaw for sustaining the latter in different adjusted positions and movable into and out of locking engagement with the toothed rod, and an operating rod rotatable at will to lock and unlock the sustaining member and movable endwise to effect its adjustment.

5. In a line casting machine, the combination of an adjustable line confining jaw, a

relatively fixed toothed rod, an intermediate sustaining member for the jaw, a slide wherein said member is movably mounted, said slide being adjustable lengthwise of and relative to the toothed rod, and unitary means for operating at will for adjusting the slide and for moving the sustaining member into and out of locking engagement with the toothed rod.

6. In a line casting machine, the combination of an adjustable line confining jaw, a relatively fixed toothed rod, an intermediate sustaining member for the jaw, an adjustable slide wherein said member is movably mounted, an eccentric for moving the sustaining member into and out of locking engagement with the toothed rod, and means for adjusting the slide and operating the eccentric.

7. A combination as specified in claim 1, characterized by the fact that the toothed rod therein recited is round in cross-section and formed with annular teeth, and that the said sustaining member is formed with a corresponding toothed cavity adapted to mesh or interlock with the teeth of the rod.

8. In a line casting machine, the combination of an adjustable line confining jaw, a relatively fixed toothed rod, an intermediate sustaining member for the jaw, an adjustable slide wherein said member is movably mounted, and an operating rod movable endwise to effect the adjustments of the slide and rotatable to move the sustaining member into and out of locking engagement with the toothed rod.

9. A combination as specified in claim 8, characterized by the fact that the operating rod therein recited is provided with an eccentric pin adapted by a partial rotation of the rod in opposite directions to move the sustaining member into and out of locking engagement with the toothed rod.

10. In a line casting machine, the combination of a vise frame, a line confining jaw adjustably mounted therein, a relatively fixed toothed rod, a slide also mounted in the vise frame, a sustaining member for the jaw movably mounted in the slide and formed with teeth to cooperate with those of said rod, and an operating rod movable endwise to adjust the slide and adapted by a half rotation in opposite directions to move the sustaining member into and out of locking engagement with the toothed rod.

11. A combination as specified in claim 10, characterized by the fact that the operating rod therein recited is extended beyond the vise frame and provided on its front and rear edges with a pair of scales arranged in inverted relation to each other, for the purpose described.

12. A combination as specified in claim 10, characterized by the fact that the operating rod therein recited is round in cross-section and slidably mounted in a bearing block se-

cured to the vise frame, and that the bearing block is provided with an indicating finger or pointer arranged to cooperate with scales carried by the operating rod.

5 13. A combination as specified in claim 1, characterized by the fact that the toothed rod is adjustable endwise for bastard settings of the vise jaw.

10 14. A combination as specified in claim 10, characterized by the fact that the toothed rod is supported between its ends to give it the required rigidity.

In testimony whereof, this specification has been duly signed by:

15 JAMES G. McNAMARA.
